UNITED STATES PATENT OFFICE.

FRANK B. YINGLING, OF HAMILTON, OHIO, ASSIGNOR TO THE CERAMIC MACHINERY COMPANY, OF HAMILTON, OHIO, A CORPORATION OF OHIO.

MACHINE FOR COATING TILE, TERRA-COTTA, &c.

1,196,831.

Specification of Letters Patent.

Patented Sept. 5, 1916.

Application filed June 14, 1913. Serial No. 773,723.

To all whom it may concern:

Be it known that I, FRANK B. YINGLING, a citizen of the United States, and resident of Hamilton, county of Butler, State of Ohio, have invented certain new and useful improvements in Machines for Coating Tile, Terra-Cotta, &c., of which the following is a specification.

The present invention relates to an improvement in machines for applying to desired surfaces of ceramic articles, and particularly tile, terra cotta or brick, a liquid coating which by a subsequent "burning" operation will be converted into a hard glass-like material. The composition of the liquid coating employed is varied according to the color desired for the finished glazed surface, the character of the material from which the article to be coated is formed, etc.

In the accompanying drawings, Figure 1 is a plan view of an embodiment of the invention, the several parts being shown more or less diagrammatically; Fig. 2 is a side elevation, partly in section, of the machine; Fig. 3 is a transverse sectional view substantially on the line 3—3 of Fig. 2; Figs. 4 and 4^a are detail views; Fig. 5 is a side elevation, more or less diagrammatic, illustrating a modification of the invention; Fig. 6 is a transverse sectional view of the same; Fig. 7 is a detail view of one of the grippers shown in Figs. 1 to 3; Fig. 8 is a detail sectional view on an enlarged scale of a part of the means for driving one of the trimming wheels; Fig. 9 is a detail showing a part of the nozzle adjusting devices detached; Fig. 10 is a detail view.

Referring to the drawings, it will be seen that the machine comprises a suitable supporting frame within which are supported one or more receptacles 1 for holding liquid coating or glaze forming material. Only one of such receptacles is illustrated in the drawings. It is frequently necessary or desirable to apply two or more layers of coating material to the surfaces to be glazed and therefore the machine preferably includes at least two receptacles 1, each being provided with means such as hereinbefore described for conveying the coating fluid to the surfaces to be treated. For example if bricks formed of relatively coarse clay, are to be treated a finish coating of finer clay or enamel may be first applied by one of said sets of coating means and a second coating

of glaze material applied to the same surfaces by the second set of coating means.

The receptacle 1 is mounted to rotate about a vertical axis and for this purpose the bottom 2 thereof is suitably geared to a power mechanism, as in Fig. 6 for example. In the receptacle is suitably supported a tube 4 which is inclined as shown and has its lower end deflected or bent laterally so that the action of centrifugal force produced by rotating the receptacle 1 will cause the liquid therein contained to enter and flow upwardly through said tube. The tube 4 has its upper end connected by a flexible conduit 7 with a nozzle or coating device 6 that is supported by the framework of the machine in a manner to be hereinafter more particularly described. The nozzle or coating device 6 is preferably made in the form shown, being substantially rectangular in cross section and having the outlet or discharge opening 6' formed in its top surface with its greatest dimension extending parallel to the direction in which the articles to be treated are moved thereover.

Beneath the member 6 of the coating devices is arranged a drain pan or basin for receiving the surplus coating liquid flowing from the opening 6' and not adhering to the articles to be coated, said drain pan being connected with the receptacle 1 by a return pipe or conduit 8.

By the construction described it will be seen that by rotating the receptacle 1 a continuous circulation of the coating liquid will be maintained through said receptacle and the nozzle 6. The particular construction of means hereinbefore described for effecting circulation of the coating liquid is not an essential part of the present invention and no claim is herein made thereto. It will be evident that any means for effecting a continuous flow of coating liquid from a suitable receptacle to a distributing nozzle may be employed instead of the one described, which however has been found to operate satisfactorily.

The articles to be treated are successively moved across the opening of the nozzle of the coating devices with the surfaces thereof which are to be coated in the path of the liquid flowing from said nozzle. As shown, in Figs. 1 to 3 the conveying means comprises two endless chains 10 which are supported by sprockets carried by vertical 105

shafts mounted in suitable bearings and 5 housings adjacent opposite ends of the machine frame, said chains being shown as guided by channel bars 5. It will be seen that each link of the chain carries a gripping plate or member 11 which is yieldingly 10 pressed outward by a suitable spring and that each link is provided with guide rolls 12, 13, engaging flanges on the guiding beams 5. The gripping members 11 of the 15 two chains are arranged in alinement and so spaced that each pair thereof is adapted to securely grip the article to be treated, as it is passed into the space separating the members of the conveyer and the parts are so related that the article will project below 20 said grippers and be maintained in a horizontal position. While the machine is adapted for coating various forms of articles, the drawing illustrates it as employed for coating brick, but in this description the term "brick" is not intended to be understood as limited to an article of the exact form illustrated.

25 The vertical shafts of the driving sprockets 14 are connected by bevel gears with a shaft 15 adapted to be connected with an alined driving shaft by a clutch 16, said driving shaft having secured thereon a power pulley 17. Manipulation of the clutch 16 is effected by a rock shaft 18 extending longitudinally of the machine and provided with an operating handle or lever 19. To maintain the desired tautness of the 30 chains 10 of the conveyer, the idler sprockets therefor are subjected to the action of suitable springs 21.

As shown, the brick are introduced between the gripping members of the conveyer 40 by means comprising two endless belts 22, 23, between which may be arranged a rotating brush 24 adapted to clean the lower surface of the brick to which the liquid coating is to be applied, and a generally similar discharge belt 25 is provided to receive the coated brick as they are released by the grippers 11. The discharge belt 25 is arranged in a plane slightly below that of the lower surfaces of the bricks while passing the coating 45 devices so that the bricks are delivered from the grippers without danger of being damaged by being dragged over the belt. If the belt 25 should become sufficiently damp from the moisture remaining on the coated surfaces 50 of the bricks it might cause the enamel or glaze coating to adhere thereto more firmly than to the brick, thus drawing said coating from the brick. To avoid this a heating device 26 may be provided so that 55 the belt will be maintained in proper dry condition.

In coating certain kinds of brick, it is necessary to moisten or dampen the surface to be coated before applying the liquid glaze 60 thereto and for this purpose a roll 27 sup-

ported to turn in a pan 28 containing water may be provided between the feed belt 23 and the coating devices, said roll being so positioned and of such contour that it will contact with the surfaces of the bricks to be 70 coated as they pass thereover.

Experience with machines of this character has shown that if the brick are carried over the coating devices with their adjacent ends abutting the separation thereof at the 75 discharge end of the conveyer frequently causes a slight crushing or break of the damp corners. Therefore it is preferred to separate the bricks slightly and this is accomplished by the use of angle shaped plates 80 29 which are manually inserted between the bricks as they pass over the feed belt 22.

An important feature of the present invention is that the brick are supported in a truly horizontal position while being coated 85 and during the coating operation are engaged at points above the surfaces to which the coating is applied. If the bricks are held in an inclined position when the coating is applied, the liquid will flow toward 90 the lower end thereof and thus the coating will not be of uniform thickness over the entire surface treated. It is also important that the coating be applied only to the lower surfaces of the bricks and not allowed to 95 flow upwardly over the sides. For this purpose the outlet of the nozzle 6 is as shown preferably made of less width than the brick and the liquid is caused to flow upwardly and then laterally across the lower surface 100 of the brick. To insure however that any of the coating which may flow upward at the edges of and adhere to the sides of the brick shall be removed, the machine is provided with cutting or grinding devices adapted to 105 yieldably contact with the sides of a brick after the same has passed the coating devices. As shown these cutters are formed as bevel disks 30 arranged at an angle to the line of travel of the bricks and supported by 110 shafts 32, which are supported in pivotally mounted bearings 31. Suitable springs are provided to normally force said disks 30 in 115 to position to contact with the sides of a brick. A guide roll 33 is connected with 120 each of said shaft bearings and adapted to contact with the brick to properly position the cutting disk relative thereto.

The means referred to for supporting and actuating the cutters 30 is shown more or 125 less conventionally in Figs. 1 and 4 and a part thereof in enlarged sectional detail in Fig. 8. As shown in the latter the shaft 32 is made in two sections connected by a universal joint 32^a and the sprocket 32^b at the 130 outer end of said shaft is connected by a chain with a sprocket on a counter-shaft 32^c journaled in suitable bearings on the frame-work of the machine and itself driven through suitable sprockets and a chain 135 140

from the main driving shaft 15. The driving connections between the shafts 32 and counter-shaft 32^c permit the necessary slight swinging movement of the bearing or housing 31 for the cutters 30 to maintain said cutters in proper contact with the brick passing between them. Such cutting devices will effectually remove any of the coating which may have adhered to the sides of the brick without damaging the brick, and by employing such cutting means it is not essential that the discharge opening of the nozzle be of less width than the brick.

In order that the coating devices may be readily cleaned, the frame by which the nozzle and drain or overflow pan are supported is mounted so that it may be adjusted vertically. As shown, said frame is carried by two arms 34 which are journaled upon a rock shaft 35 mounted in suitable bearings on the main frame and said shaft is provided at one end with an operating handle 36. A counter balance spring 37 is arranged to bear against an arm 35^a depending from the shaft 35. The spring 37 is supported by a rod or bolt 37^a projecting from a member of the main supporting frame and passing through an opening in said arm 35^a. A nut or head at the outer end of this rod forms an abutment for the spring 37. To insure that the nozzle will be maintained in the desired horizontal relation to the brick, and the endless conveyer by which the brick are moved over the coating mechanism, a link 40 is pivotally connected with a portion of the nozzle supporting frame and the main frame of the machine. The distance between the pivotal centers of the arms 34 and link 40 being the same, insures parallel motion of the members and the nozzle is maintained horizontal in either its upper or lower position and adjustable stops are provided for coöperating with the handle 36 to hold the nozzle in either of said positions. As shown in Fig. 10, two lugs are suitably connected with the lever 36 and with these are adapted to coöperate two pivotally mounted manually adjustable stops 36^a, 36^b, by which the lever and liquid nozzle may be held in either of the two positions referred to.

The channel beams 5, by which the chains 10 are supported and guided are adapted to be adjusted transversely relative to each other to adapt the machine for coating articles of different widths. As shown said beams are engaged by suitably threaded shafts 41, 42, mounted on the frame of the machine and having bevel pinions 43, 44 with which engage similar pinions on a shaft 45 that is provided at one end with a wheel 46 by which it may be turned.

In Figs. 5 and 6 there is illustrated a slightly modified form of the invention which is designed to prevent the coated sur-

face of the bricks from coming in contact with any part of the mechanism. With certain classes of brick there is a possibility of the appearance of the coated surface being marred or the brick slightly damaged by contact with the delivery belt 25; and the embodiment of the invention shown in Figs. 5 and 6 is particularly designed for avoiding such results.

The coating devices of this form of machine are the same as those previously described but the brick are supported by small trucks arranged to run in a track 50 of substantially elliptical form in side elevation and composed of suitably shaped channel bars. The wheels 52 of the trucks run in the channels in the bars forming the track 50 and each truck comprises two elastic faced clamping members 53 and an intermediate spring 54 which acts to separate said members so that a brick may be readily inserted in or removed from the truck.

Guide members 55 extending throughout the greater portion of the length of the track 50 coöperate with compression rolls 56 to hold the members 53 in close engagement with the brick inserted between them.

In using the machine the brick are successively inserted in the trucks positioned about the point A in Fig. 5 and the trucks manually moved along the track to the right, between the compression guides 55 and into position beneath friction driving rolls 58. These rolls as shown are connected by suitable gearing with the shaft 59 by which the receptacle 1 for the liquid coating material is rotated, which shaft is provided with a driving pulley 60. A brush 61, shown as connected with the drive rolls is provided to clean the surfaces of the bricks to be coated as they are carried past it.

As shown several trucks are assembled in the lower run way of the track 50 contacting one with the other and are forced over the coating devices by the action of the rolls 58. Each truck is provided at one end with a partition which acts to separate the brick in one truck from that in the following or preceding one in the same manner and for the purpose that the plates 29 are employed with the machine illustrated in Figs. 1 to 3. When a truck has been thus moved past the coating devices and into the upper run way of the track 50, it will be seen that the coated surface of the brick therein will be uppermost and as the truck has passed beyond the compression guides 55 the spring 54 separates the clamping members of the truck so that the coated brick may be readily removed for conveyance to the burning kiln.

The machine may of course be provided with means such as previously described for removing any of the coating which may flow up on and adhere to the sides of the brick.

The members of the track 50 are adapted

to be adjusted toward and from each other by means of suitably threaded shafts and a controlling hand wheel 63, so that the machine is adapted for coating bricks of different thickness.

In the accompanying drawings most of the parts are shown more or less diagrammatically as there can manifestly be many changes, for example in the detail construction of the frame, the driving mechanism, &c., without departing from the invention. In practice it is customary to provide the machine with at least two sets of coating devices, it having been found preferably in treating many classes of brick to apply two coatings of the liquid instead of a single heavier or thicker coating. In view, however, of the size of the parts, it has been deemed inadvisable to illustrate more than one set of such coating devices in the accompanying drawings.

As hereinbefore noted, the devices particularly illustrated and hereinbefore described are designed for coating flat surfaces, but it will be evident that the invention can be readily embodied in a form adapted to coat irregular surfaces such as are known to the trade as trimmings, moldings, cap and base and relief designs.

Having described my invention what I claim as new and desire to secure by Letters-Patent is,

1. In a machine for applying a liquid coating to a brick, the combination with a nozzle and means for supplying liquid coating material thereto, of means arranged to grasp a brick and carry it into and from a position where the surface to be coated will be in the path of liquid issuing from the nozzle, said brick engaging and supporting means being continuously out of contact with the surface to be coated and out of the path of the liquid coating liquid.

2. In a machine for applying a liquid coating to a brick, the combination of a nozzle arranged to discharge liquid coating material in an upward direction, a conveying means moving across the mouth of the nozzle above the path of liquid issuing therefrom and adapted to engage a brick at points above the surface thereof to be coated and to carry said surface into and from the path of the liquid discharged by the nozzle.

3. In a machine for applying a liquid coating to brick, the combination of a receptacle for liquid coating material, a discharge nozzle connected with the receptacle, means for engaging opposite sides of a brick and carrying it across the nozzle with the surface to be coated in the path of liquid flowing from the nozzle and out of contact with the supporting means, and means for continuously circulating the liquid coating material through the receptacle and nozzle.

4. In a machine for applying a liquid

coating to brick, the combination of a receptacle for liquid coating material, a discharge nozzle connected with the receptacle, means for moving a brick over the nozzle in a direction parallel to the longest dimension of the nozzle outlet with the surface to be coated in the path of liquid flowing from the nozzle.

5. In a machine for applying a liquid coating to brick, the combination of a receptacle for liquid coating material, a discharge nozzle connected with the receptacle, means for moving a brick over the nozzle in a direction parallel to the longest dimension of the nozzle outlet with the surface to be coated in the path of liquid flowing from the nozzle, the width of the nozzle outlet being less than that of the surface to be coated.

6. In a machine for applying a liquid coating to brick, the combination with a receptacle for liquid coating material, and means for delivering liquid from said receptacle in an upward direction, of means for supporting a series of brick and carrying them across the path of liquid withdrawn from the receptacle, said means engaging opposite sides of the bricks beyond the surface to be coated.

7. In a machine for applying a liquid coating to brick, the combination with a receptacle for liquid coating material, and means for delivering liquid from said receptacle in an upward direction, of means for conveying a series of brick past said liquid delivering means and including frictional gripping devices adapted to engage the bricks at points outside of the area of surfaces to be coated.

8. In a machine for applying a liquid coating to brick, the combination with a receptacle for liquid coating material, and means for delivering liquid from said receptacle in an upward direction, of means for supporting a series of brick by engagement with opposite sides thereof and conveying them past the liquid delivering means with their lower surfaces in position to be uniformly coated with said liquid, the engagement of the conveying means with the brick being above the path of the coating liquid and means for removing any coating that flows onto the sides of the bricks.

9. In a machine for applying a liquid coating to brick, the combination with a receptacle for liquid coating material, and means for delivering liquid from said receptacle in an upward direction, of means for supporting a series of brick and conveying them past the liquid delivering means with their lower surfaces in position to be uniformly coated with said liquid, and abrading means arranged to automatically act upon the sides of each brick after it has passed the coating devices.

10. In a machine for applying a liquid coating to brick, the combination with a

- receptacle for liquid coating material, and a nozzle arranged to deliver liquid from said receptacle in an upward direction, of means for supporting a series of brick and 5 moving them past the nozzle with the surfaces to be coated in the path of liquid flowing therefrom, and means projecting into the space separating and preventing contact between successive bricks in the series 10 while passing over the coating devices.
11. In a machine for applying a liquid coating to brick, the combination of elevated conveyer means adapted to support a series of brick with the surfaces to be coated depending therefrom and held in horizontal position, and liquid coating means including a nozzle arranged below and having its outlet parallel with the surfaces to be coated as the brick are carried over the 20 nozzle by the conveyer.
12. In a machine for applying a liquid coating to brick, the combination of a supporting frame, a receptacle for liquid coating material, a nozzle connected with said 25 receptacle and adapted to discharge liquid in an upward direction, conveying means adapted to support a series of brick and carry them over the nozzle with the surfaces to be coated depending therefrom and held 30 in horizontal position, and means for removing any coating that may flow upwardly on to the sides of the bricks.
13. In a machine for applying a liquid coating to brick, the combination of a supporting frame, a receptacle for liquid coating material, a nozzle connected with said 35 receptacle and adapted to discharge liquid in an upward direction, conveying means adapted to support a series of brick and carry them over the nozzle with the surfaces to be coated depending therefrom and held 40 in horizontal position, a brush adapted to contact with the surfaces to be coated before the bricks pass the coating devices, and means for removing from the sides of each brick any coating adhering thereto.
14. In a machine for applying a liquid coating to brick, the combination of a supporting frame, a receptacle for liquid coating material, a nozzle connected with said 45 receptacle and adapted to discharge liquid in an upward direction, conveying means adapted to support a series of brick and carry them over the nozzle with the surfaces to be coated depending therefrom and held 50 in horizontal position, and means for adjusting the nozzle vertically.
15. In a machine for applying a liquid coating to brick, the combination of a supporting frame, a receptacle for liquid coating material, a nozzle above the receptacle, means for forcing liquid from the receptacle through the nozzle, conveying means 55 for supporting a series of bricks and carrying them past the nozzle with the surfaces
- to be coated arranged in horizontal position in the path of liquid flowing from the nozzle, and means for adjusting the nozzle vertically.
16. In a machine for applying a liquid coating to brick, the combination of a supporting frame, a receptacle for liquid coating material, a nozzle above the receptacle, means for forcing liquid from the receptacle through the nozzle, a drain pan supported below the nozzle and connected with the liquid receptacle, conveying means for supporting a series of bricks and carrying them past the nozzle with the surfaces to be coated in the path of liquid flowing from the nozzle, and means for adjusting the nozzle and drain pan vertically. 75
17. In a machine for applying a liquid coating to brick, the combination with a receptacle for liquid coating material and a nozzle connected with the receptacle and adapted to deliver liquid therefrom in an upward direction, of means for conveying bricks past the nozzle with the surfaces thereof to be coated in the path of liquid flowing from the nozzle, said conveying means engaging opposite sides of a brick, and positioning the coated bricks with the coated surfaces uppermost, substantially as 80 described. 85
18. In a machine for applying a liquid coating to brick, the combination with a receptacle for liquid coating material, and a nozzle connected with the receptacle and adapted to deliver liquid therefrom in an upward direction, of guide ways comprising two substantially parallel sections arranged one above the other, and a series of brick supporting trucks mounted to move along said ways, the bricks being carried past the nozzle with the surfaces to be coated in the path of liquid flowing therefrom as the trucks traverse the lower of said parallel sections and having their coated surfaces uppermost when the trucks are on the uppermost of said sections. 90 95
19. In a machine for applying a liquid coating to brick, the combination with a receptacle for liquid coating material, and a nozzle connected with the receptacle and adapted to deliver liquid therefrom in an upward direction, of means for conveying bricks past the nozzle with the surfaces thereof to be coated in the path of liquid flowing from the nozzle and comprising a plurality of pairs of clamping members, each pair being adapted to engage the sides of a brick at points beyond the margins of the surface to be coated. 100 105 110
20. In a machine for applying a liquid coating to brick, the combination of an elevated frame formed of channel bars, a receptacle for liquid coating material, means for delivering liquid from the receptacle in an upward direction beneath said frame, 115 120 125
- 130

means for conveying brick past the delivering means with the surfaces to be coated in position to receive liquid therefrom and comprising a series of pairs of clamps supported by means guided in the channel bars of the elevated frame, and means for varying the distance separating the channel frame bars to adapt the machine to support bricks of different thickness.

- 10 21. In a machine for applying a liquid coating to brick, the combination of an elevated frame formed of channel bars, a receptacle for liquid coating material, means for delivering liquid from the receptacle in 16 an upward direction beneath said frame, means for conveying bricks past the delivering means with the surfaces to be coated in position to receive liquid therefrom and comprising a series of pairs of clamps supported by means guided in the channel bars of the elevated frame, a plurality of threaded shafts engaging said channel frame bars, and a control shaft geared to said threaded shafts, whereby the clamps are adapted to 26 properly engage bricks of different thickness.

22. In a machine for applying a liquid coating to brick, the combination of a receptacle for liquid coating material, means 30 for delivering liquid from said receptacle in an upward direction, a guide way formed of parallel channel bars above the liquid de-

livering means, a series of brick supporting clamps adapted to move longitudinally of said guide way past the liquid delivering 35 means while maintaining the surfaces of the bricks therein to be coated in the path of liquid delivered by said means, and means for automatically releasing each clamp after it has passed the liquid coating means. 40

23. In a machine for applying a liquid coating to brick, the combination of a receptacle for liquid coating material, means for delivering liquid from said receptacle in an upward direction, a guide way formed of 45 parallel channel bars above the liquid delivering means, a series of trucks supported by said channel bars and each comprising two clamping jaws adapted to engage opposite sides of a brick and support the surface to be coated in position to receive liquid from said delivering means as the brick is carried thereby, a spring acting constantly to separate the jaws of each truck, and relatively stationary guides arranged to coöperate with the clamps to maintain them in 50 closed relation.

In testimony whereof I affix my signature in presence of two witnesses.

FRANK B. YINGLING.
